(57) CLAIM

The ornamental design of a chair, as shown and described.

DESCRIPTION

FIG. 1 is a perspective view of a chair showing our new design;

FIG. 2 is a left side view thereof;

FIG. 3 is a front view thereof;

FIG. 4 is a rear view thereof;

FIG. 5 is a top view thereof;

FIG. 6 is a left side view of a chair showing a design according to a second embodiment;

FIG. 7 is a rear view of the chair of FIG. 6;

FIG. 8 is a perspective view of a chair showing a design according to a third embodiment; and,

FIG. 9 is a left side view of the chair of FIG. 8.

The broken lines showing a tablet arm in FIGS. 8 and 9 are for illustrative purposes only and form no part of the claimed design.
